WINDING APPARATUS

Lester Campbell, Westfield, Mass., assignor to
 Foster Machine Company, Westfield, Mass., a
 corporation of Massachusetts

Application November 15, 1939, Serial No. 304,499

19 Claims. (Cl. 242—43)

The present invention relates to new and useful improvements in winding machines particularly adapted for the winding of packages of yarn or thread.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate embodiments of the invention, and together with the description, serve to explain the principles of the invention.

Of the drawings:

Figure 1 is a side elevation of a typical and illustrative embodiment of the present invention, certain of the conventional driving and supporting parts being broken away and omitted;

Figure 2 is an end elevation of the embodiment shown in Figure 1;

Figure 3 is a fragmentary side elevation of the embodiment of the invention shown in Figs. 1 and 2;

Figure 4 is a similar fragmentary side elevation of the parts shown in Figure 3 when the package has been fully wound;

Figure 5 is an end elevation of the parts shown in Figure 4;

Figure 6 is a fragmentary side elevation of a modified embodiment of the invention;

Figure 7 is a fragmentary end elevation of the embodiment of the invention shown in Figure 6;

Figure 8 is a fragmentary top plan view showing still another modification of the invention;

Figure 9 is a similar view showing certain of the parts held against pivotal movement;

Figure 10 is a sectional view taken on the line 10—10 of Figure 9;

Figure 11 is a sectional view taken on the line 11—11 of Figure 9;

Figure 12 is a detailed plan view showing a supplementary part which may be used to assist in holding certain of the parts against pivotal movement;

Figure 13 is a fragmentary end view showing the means for pivotally moving the guiding plate as the package increases in size;

Figure 14 is a fragmentary top plan view of 55

the parts shown in Figure 13, the parts being positioned as they are at the beginning of the winding of a package;

Figure 15a is a side elevation of a counter-weight;

Figure 15b is an end elevation of the counter-weight of Figure 15a;

Figure 15c is an end elevation of a larger counterweight;

10 Figure 16 is an end elevation of a modified form of the invention, the package being shown in dotted lines;

Figure 17 is a similar view with the parts shown in their full-package position;

15 Figure 18 is a detailed fragmentary side elevation of the mounting of certain parts in Figures 16 and 17;

Figures 19 to 25a are side elevations of a few of the various types of packages which can be wound according to the present invention, together with diagrammatic illustrations of the shape of the parts which produce the respective packages; and

20 Figure 19 shows a cone package with a concave nose and convex base, otherwise known as the "Foster Standard" which may be wound by use of the present invention;

Figure 19a shows the relative position of the slots of the thread guiding surfaces used in producing the package of Figure 19;

25 Figures 20 and 20a show a cone package with both ends straight or at right angles to the axis of the cone spindle together with the slots of the thread guiding surfaces which result in such a package;

Figures 21 and 21a show a cone package with both ends tapered or convex, and the slots of the thread guiding surfaces which produce this package;

30 Figures 22 and 22a show a cone package having a tapered base, and the slots of the thread guiding surfaces which produce the package;

Figures 23 and 23a show a cone package having a tapered nose and the respective thread 35 guiding slots;

Figures 24 and 24a show a compressible dyeing tube package progressively formed with the coils closer together in the middle portion and the coils wider apart at both ends of the package, together with the slots for forming such a package; and

40 Figures 25 and 25a show a cone package having an increased taper progressively formed with the coils closer together at the base and with the coils wider apart at the nose, together with

the slots of the thread guiding surfaces which cooperate to produce such a package.

The present invention has for its object the provision of a novel and improved winding machine for winding packages of yarn or thread which by the interchange of a few simple parts can be adapted for winding an unusually large variety of packages. A further object of the invention is the provision of a winding machine which is durable in construction, and involves no complex mechanical motions for controlling and varying the traverse of the thread across the rotating package. Still another object of the invention is the provision of a winding attachment which can be easily adapted to existing types of winding machines so as to increase the variety of packages which they are capable of winding.

The invention also provides a winding machine in which the fast moving parts are of light construction which are subjected to little wear and the nature of the package produced is determined by the shape of the thread guiding surfaces. The invention further provides an improved winding machine for winding thread onto a rotating core of cylindrical or tapered shape in helical coils of any desired, constant or varying pitch to form self-supporting packages and in which the thread is guided by being passed over or through a plurality of slots or elongated thread guiding surfaces which are relatively movable and have their slots or other thread guiding surfaces intersecting so that their relative movement accurately and positively controls the position of the thread along the rotating package.

In accordance with the illustrative embodiment of the invention which is shown as applied to a winding machine for winding packages supported on and rotated about a fixed axis, means are provided for rotating the cylindrical or conical core at a relatively high speed and the traverse of the thread or yarn along the rotating core is controlled by a plurality of thread guiding members, one of which generally moves back and forth along the package while another is either fixed with reference to the surface of the package or may be angularly moved about an axis substantially normal to that surface. One of the thread guiding members is preferably in contact with the surface of the package and is mounted on a swinging frame so that it may move away from the core axis and yet remain in contact with the surface of the package as the package builds during the winding operation, and it may also be provided with means for equalizing its pressure against the package surface so that its pressure is uniformly distributed over the package.

The thread guiding member in contact with the package surface is preferably provided with an elongated thread guiding surface which may be in the form of a slot and this surface may be straight, curvilinear, angular, continuous or interrupted and may be held in a fixed position with reference to the rotating package surface or it may be mounted so that its thread guiding surface is movable angularly with reference to the package axis and surface.

The cooperating thread guiding member generally comprises a slotted member moving back and forth across the surface of the package, its speed of reciprocation or oscillation relative to the rotation of the package spindle being determined by the number of coils of thread which are to form one of the helical layers of the pack-

age. The thread guiding surface or slot of this member may also be straight, angular or curvilinear and is preferably so positioned relative to the first thread guiding member that the two thread guiding slots or surfaces lie closely adjacent to each other with their slots superposed and at a relatively great angle.

As the two cooperating thread guiding members and their surfaces or slots are relatively 10 moved the point of crossing of these surfaces or slots changes, and as the thread passes through both slots or over both surfaces under some tension, its position along the surface of the package being wound is determined by and corresponds to 15 this point of crossing thereby causing the thread to be traversed along the package. The traverse of the thread may, obviously, be varied either by changing the relative position of the slots or by a combination of such changes. In this way a 20 very precise control may be had of even a complex wind solely by varying the shape of the relatively movable thread guiding means, and a wide variety of packages such as can be produced otherwise only by an equally wide variety of machines can be produced by a single machine and a 25 relatively few interchangeable parts.

It will be understood that the foregoing general description and the following detailed description as well are exemplary and explanatory of the invention but are not restrictive thereof.

Referring now in detail to the illustrative embodiment of the invention as shown in Figures 1 to 5 and 13 to 15 of the drawings, the invention is applied to a winding machine adapted to wind thread or other strand material onto a core from any desired supply through thread tensioning devices and under control of thread guiding means. A main stationary housing 4 supports the rotatable driving spindle 2 and a rotatable shaft 3 upon which is fastened the main traverse cam 4 connected to reciprocate the thread guide 5 carried by a guideway frame 6 which is mounted in the usual manner for swinging about the shaft 3, against the tension of a spring 8. A second thread guiding plate 7 is provided between the guide 5 and the surface of the package being wound on spindle 2.

Thread guide 5 is connected for reciprocation by the main traverse cam 4 through the traverse tube 9 which is slidably mounted on the guide rod 10 carried on the swinging frame 6. At one end tube 9 carries a cam follower 11 which runs in the cam groove 12, while at its other end it is connected to the bracket 13 which supports the thread guide 5, this thread guide being held in a fixed vertical position by means of the guideway members 14 and 15 so that it reciprocates in close proximity to the package surface engaging thread guiding plate 7.

Thread guiding means 5 is formed with a thread guiding slot 5a, which is more or less vertical, and plate 7 is formed with a thread guiding slot 7a which is more or less horizontal, these slots crossing each other in all their positions.

Means are provided for varying the angular position of the slot in the plate 7 as the package increases in size during the winding operation and for this purpose a bracket 18 supports a short stud 19 upon which is rotatably mounted a double grooved pulley 20, bracket 18 being mounted on the guideway frame 6, and bracket 21 supporting one end each of the flexible steel bands 22a and 22b respectively fastened to the

spindle bearing housing 23, the other ends of the steel bands 22a and 22b being wrapped around and fastened in the grooves 20a and 20b of the pulley 20. As the pulley 20 is moved bodily in one direction by swinging of the frame 6, as the package builds, it rolls along the flexible bands 22a and 22b, unwinding one band from the surface of the pulley as the other band is wound on the pulley, thereby rotating the pulley 22 and its arm 24 which is linked to an end of pivoted plate 7 by means of link 25. A lever 24 provided with a series of holes 24' is fastened to one side of the grooved pulley 20, and link 25 is connected at one of its ends to one end of the thread guide plate 7, while its other end is pivotally mounted in one of the lever holes 24'. On the other side of the pulley 20 is mounted another lever 27 near the end of which is adjustably mounted a counterweight 28a, shown in detail in Figures 15a, 15b, 15c to overcome the effect of the swinging frame balancing spring 8, thereby counteracting the effect of the spring 8 on the pressure between the guide plate 7 and the package.

As illustratively shown in Figures 1 to 5, the thread guiding plate 7 is pivotally mounted to incline the thread guideway by means of a pivot stud 136 which projects from an adjustable bar 37 said bar being adjustably fastened to the yoke 31 by screws 38 and 38' and said yoke 31 being fastened to the plate 7 near its ends. The pivot stud 136 is mounted in a cradle bearing 138 from which extends the vertical pivot stud 132 which is supported in the split bearing 131 of the bracket 130, said bracket 130 being adjustably secured to the inner face of the bar 33 extending the length of the guideway and secured in suitable aligned position by means of the supports 35 and 35' mounted on studs 34 and 34' projecting upwardly from the guideway frame 6. Yoke 31 is spaced from plate 7 for most of its length so as to provide a narrow parallel-sided slot in which the thread guide 5 may reciprocate. Between the ends of yoke 31 and bar 33 are provided series of holes for screws 38 and 38' and 54 and 54' respectively. The adjustable bar 37 and the bracket 130 are provided with slots for longitudinal adjustment, thus the adjustable bar 37 is adjustably fastened to yoke 31 by means of screws 38 and 38' and the bracket 130 is adjustably fastened to bar 33 by means of screws 54 and 54' so that the longitudinal positions of the axes of pivot studs 132 and 136 may be varied to accommodate the winding of different lengths of packages and permit the pivots 132 and 136 to be positioned substantially centrally of the package being wound, also to permit the pivots 132 and 136 to be positioned either side of the central position of a package being wound.

An advantage of providing means to pivot the guide plate 7 either side of a relatively central position is that it is possible to use a single slanting reciprocating guide such as 5 with an adjustably longitudinally positioned horizontal pivot which provides for the plate 7 to swing with one end, such as the nose end, in a relatively lesser radius and arc and the other end, such as the base end, in a relatively greater radius and arc for the purpose of producing a package with less taper at one end such as the nose and more taper at the other end such as the base.

By comparing the two settings, it should be noted that with a relatively central position of the horizontal pivot and a single slanting traverse guide, a package is built up with the same

taper in each end, and with a position of the horizontal pivot nearer the nose, a package is built with less taper at the nose and more taper at the base and using the same single slanting traverse guide in both instances.

Guide plate 7 is connected with the means for angularly shifting its position by means of the link 25 which is pivotally connected to a pivoted stud 41 projecting from one of the holes 24' in the lever arm 24 connected to the double pulley 20, while the other end of the link 25 is pivotally connected to a short stud 43 projecting from and pivotally mounted on the end of the guide plate 7, so that the angular position of the guideway is controlled in all its positions by the position of the swinging frame 6 through the steel bands 22a and 22b, pulley 20 and the associated parts.

Means are also provided for steadyng the plate 7 so that it tilts in a plane which is fixed with reference to the swinging frame 6 and for this purpose an arcuate guideway 128 is formed with a curved slot 127 which fits over an end of the guide plate 7, the radius of curvature of the slot 25 corresponding to the radius of the plate 7, and this guideway 128 is securely supported on the swinging frame and fixed thereto by means of the support 35 so that it is beyond the nose of the package and does not interfere therewith.

Thus the guide plate 7 is tangent to the surface of the package and is pivotally mounted about an axis normal to the tangent plane so that it may be tilted to vary the traverse of the thread on the packages as the thread is moved a constant distance by the thread guide 5, thereby varying the shape of the package wound.

Figures 1 and 2 show the arrangement of the parts at the beginning of winding of a tapered end package such as is shown in Figure 21. Figure 3 shows the parts more in detail, the slot in guide plate 7 being in its initial horizontal position, while the thread guide 5 is shown in its two extreme positions of reciprocation, the full line position being the right hand end of its traverse 45 while the dotted line showing of thread guide 5 shows the thread guide at its extreme left hand position. It will be noticed that the movement of the thread guiding slot 5a along the horizontal guide plate slot 7a (which is longer than the package to be wound) is equal to the movement of the thread guide 5 as measured along the traverse rod 10.

Figures 4 and 5 show the positions of the parts when the winding of the tapered end package has been completed and the traverse of the thread along the package is considerably shorter than the traverse of the thread guide 5. It will be noticed in these figures that the swinging frame 6 has been moved to the right (Figure 5), guide plate 7 is still tangent to the surface of the package, the steel bands 22a and 22b have caused rotation of the double grooved pulley 20 to cause a rotation of the guide plate 7 about its pivot 136 so that the guide slot 7a is now inclined at a considerable angle with respect to the axis of the package. The extreme positions of reciprocation of the thread guide 5 are shown in Figure 4 and it will be seen that the distance between the extreme positions of the intersection of the thread guide slot 5a with the guide plate slot 7a is considerably less than the distance between the extreme positions of the thread guide 75 5, and that this shortening has taken place at

both ends of the package so as to produce a taper on both ends of the package.

Of course, it will be understood that the change from the initial to the final position is accomplished gradually and proportionally to the growth of the package so that the taper has the desired shape, and that this shape can be varied by suitably choosing the dimensions, positions and proportions of the various parts.

Figures 6 and 7 illustrate a modification of the invention in which means are provided for permitting the guide plate 7 to pivot, not only about its substantially horizontal axis so as to produce a variation in the traverse of the thread across the package, but also about an axis which is substantially vertical so that the guide plate 7 may remain tangential to the package and in contact with the surface of the package, but may be variably inclined with reference to the axis of the package thereby permitting the pressure between the guide plate 7 and the package to be uniformly distributed along the length of the package and producing a more uniform and softer wind of the package.

As illustratively embodied, the guide plate 7 is mounted for pivotal movement about a substantially horizontal axis normal to the axis of the package by means of the yoke 31 which is pivotally mounted by means of the stud 136 in the cradle bearings 138. Means are provided for pivotally mounting the guide plate 7 about a substantially vertical axis by pivoting the cradle bearing 138, and for this purpose a stud 132 projects downwardly from the cradle bearing 138 and is journaled in a split bushing 134 which is formed integral with a bracket 130 depending from and screwed to the cross bar 33 by screws 54 and 54'.

Guide plate 7 is connected for tilting movement by means of the double pulley 20 as in the previously described embodiment and the tilting of the guide plate is progressively increased as the package increases in diameter.

The guide plate may also move about its vertical axis and thus has universal controlled movement with respect to the package, the tilt being controlled by the diameter of the package, while the guide plate remains normally in floating contact with the surface of the package by movement about its vertical pivot 132.

When it is desired to dispense with the pressure distribution which involves the pivotal movement about the axis 132, the screw 133 may be tightened to clamp the split bushing tightly onto stud 132 and thus hold the guide plate in a fixed vertical plane. Similarly, when it is desired to wind a type of package in which the slot 7a in guide plate 7 is not progressively tilted as the package grows, it is possible to disconnect the link 25 and then hold the guide plate 7 against tilting movement by tightening the screw 137 which clamps the split bushing onto the stud 136 in its cradle bearings 138 so that it retains a constant position, such as a horizontal position of the slot throughout the winding of the package.

As with the modification previously described, the thread guide 5 is reciprocated as the spindle 2 carrying the package core is rapidly rotated. The slotted guiding plate 7 rests against the surface of the package and at the beginning of the wind, the slot 7a is horizontal or in the same plane as the package axis, but as the package builds, the guide plate 7 is swung outwardly and causes the guide slot 7a to be tilted

progressively so as to shorten the traverse of the thread at both ends of the package. However, if desired, the guide plate 7 may be locked in a fixed position so that the traverse of the thread remains constant.

Figures 8 to 11 illustrate a modification of the invention in which means are provided for tilting the guide plate 7 progressively and in accordance with the increase in diameter of the package, and in which means may be attached for steadyng the guide plate in its various tilted positions or alternatively, for permitting the guide plate to move about a substantially vertical axis so that the pressure between the guide plate and the surface of the package may be uniformly distributed as the taper of a conical package changes during the growth of the package.

In this embodiment, the package is rotated about its spindle and the thread guide 5 is reciprocated as previously described. The guide plate 7 is mounted on the swinging frame so as to have pivotal movement about two axes, one parallel to a plane tangent to the package surface, while the other axis is substantially normal to the package surface. The cross bar 33 is supported on the studs by means of the supports 35 and 35' and on the inner face of the bar is bolted a bracket 130 which extends for a considerable distance along the bar 33 and is provided with a central split journal 131 to receive the vertical pivot 132 and may be clamped tightly onto the pivot to prevent the pivotal movement by tightening the screw 133. Supported on the upper end of the pivot stud 132 is a second split bushing 135 which receives the pivot stud 136 which may be held against pivot movement by tightening the clamping screw 137, and bushing 135 is provided with an inwardly extending integral cradle bearing bracket 138 to assist in firmly supporting the plate 7 which is adjustably fastened to bar 37 by screws 38 and 38' which, in turn, is mounted at the inner end of the stud 136.

The end of the guide plate 7 is normally steadied in its pivotal movement by means of the guideway slot 127 formed in the arcuate guide portion 128 bolted to the support 35, and as previously described in connection with the other figures, the tilting movement of the guide plate 7 is controlled by the size of the package through the double pulley 20, the link 25 and their associated parts.

However, if it is desired to wind a package using the guide bar 7 in a fixed horizontal position, the link 25 may be disconnected from the machine so that the rotation of the pulleys 20 is idle, and the guide bar 7 may then be held against pivotal movement by means of the clamping screw 137 which may be tightened to firmly grip the pivot stud 136 and hold it and the guide plate 7 against pivotal movement about the pivot 136 which is substantially normal to the surface of the package.

The guide plate 7 may also be permitted to pivot about the stud 132 so that the pressure of the guide plate 7 is equalized against the surface of the package. For this type of operation, the split bushing 134 is loosened by screw 133 so as to permit turning of the guide plate about its pivot 132, and the steadyng guide 128 is removed from the support 35 so as to permit the guide plate 7 to move under the influence of the pressure of the package.

With this type of apparatus, the guide plate

7 is allowed to pivot about either or both of its axes depending upon the type of package to be wound and the change from one type of winding to the other is made by substituting the proper type of guide plate 7 in the apparatus, removing link 25 if necessary, using support 35 and adjusting the bushing tightening screws 133 and 137 to correspond with the pivotal action desired. Thus, the guide plate may pivot about its normal axis; it may pivot about its parallel axis; or it may pivot about its normal and about its parallel axis; the pivotal action in each case being controlled by the size or shape of the package.

Figures 16 to 18 illustrate a modified embodiment of the invention in which means are provided for positively controlling the angular position of the guide plate 7 with reference to the surface of the package as the tapered package increases in diameter and taper during the winding operation so as to positively maintain the guide plate always in contact with the surface of the package throughout the length of the package. Figure 16 illustrates the position of the parts at the beginning of the winding operation while Figure 17 illustrates the position of the parts at the completion of the winding of the package, the package being shown in dotted lines to clarify the showing of the other parts of the apparatus.

As the thread is wound on the package, the thread guiding parts are pushed back away from the spindle 2 causing the pulley 20 to rotate due to the bands 22a and 22b thereby causing the arm 24 mounted on pulley 20 to be rotated counterclockwise. Link 25 is pivotally connected to the arm 24 at one of its ends and at its other end it is pivotally connected to a cam plate 134. Cam plate 134 is pivotally mounted on bracket 129 by means of the stud 135 while the edge of cam 134 contacts with the end of screw 137 threadedly mounted in a lug 139 and held firmly therein by means of the jamb nut 137b.

Guide plate 7 is mounted for tilting movement about an axis normal to the surface of the package as previously described, and is also mounted for pivotal movement about an axis parallel to the plane of the guide plate 7 and to the plane normal to the surface of the package. Means are also provided for holding the guide plate fixed with reference to either of its pivotal axes so that the length of the thread traverse may remain constant, or so that the guide plate will remain parallel to the initial taper of the conical package core.

However, when the cam 134 is employed and the guide plate 7 is free to move about its vertical pivotal axis under control of the cam 134 and the actuating means therefor, the package pushes the frame 6 outwardly, causing the bands 22a and 22b to rotate the pulley 20, and this rotation is assisted by the mass of the counterweight 28, and these forces cause the arm 24 to be moved downwardly or counterclockwise, pushing the link 25 and tending to rotate the cam 134 about its stud 135. The pressure exerted on the peripheral edge of the cam 134 causes the cam 134 and the guide plate 7 to be pushed away from the spindle 2. The increasing mass of yarn on the core is the prime mover of both the guide plate 7 and the cam 134 and the combined movements cause the separation of the guide plate 7 from the core at the base of the conical package to equal the maximum amount of yarn mass wound as the package builds up.

The plate 7 being pivotally supported provides for that portion or end of the plate adjacent the nose end of the package to be swung in toward the core since there is a correspondingly minimum amount of yarn mass wound at the nose end as the package builds up. There is a greater or incremental outward movement of the plate 7 at the base of the winding package than the normal movement of the supporting guideway and a relatively lesser or decremental outward movement of the plate 7 at the nose of the winding package than the normal movement of the supporting guideway, thus the plate 7 is constantly controlled in its progressively, increasing angular relation with the core and at the same time the guide plate is progressively kept in constant contact with the increasing taper of the surface of the winding package.

Referring now to the diagrammatic views 19 to 25a showing a few of the more important types of packages which can be wound with the winding machine of the present invention:

Figure 19 shows a package 60 of generally conical exterior, wound on a conical core 61, and having a concave nose 62 and a convex base 63 which is sometimes known as a Foster Standard package. This package may be wound by the present invention by using a guide plate 7 having a horizontal or axially aligned slot 64 in combination with any form of crossing slot, such as 65, 66 or 67 in the reciprocable thread guide 5 as shown in Fig. 19a. The crossing of these slots 64 and 65, 66 or 67 lies in a straight line and the traverse of the thread lies in a straight line and is equal to the movement imparted to the thread guide 5 by the cam 4, both ends of the package 60 being perpendicular to the surface of the core 61.

Figure 20 shows a type of package 70 of generally conical exterior wound on a conical core 71 and having flat ends 72 and 73 which is sometimes known as a Universal Standard package. Such a package may be wound by the present invention by using a guide plate 7 having a straight slot or guiding surface 74 which is progressively inclined from the dotted line position at the start of the winding to the full line position at the completion of the package in cooperation with an angular slot or guiding surface 75 formed in the thread guide 5, the thread passing through the crossing T of these slots. As soon as the slot 74 has been inclined to any extent by the building of the package causing a corresponding movement of the guide members 5 and 7 away from the spindle, the traverse of the thread is shifted slightly to the right so that the ends of the package build perpendicular to the axis of the package, rather than perpendicular to the surface of the core, as in Figure 19. As will be noted, the upper half of slot 75 is inclined slightly to the right, and the lower half is inclined slightly to the left. As the slot 75 is moved to the left of its central position, by movement of the guide 5, the intersection T of the slots 75 and 74 is moved slightly less than the linear movement of the slot 75 as a whole, thereby causing a shortening of the traverse on this leftward movement of the slot 75. Similarly, the movement of the slot to the right of its central position causes a lengthening of the right hand half of the traverse so that the movement of the slot 75 as a whole is slightly greater, thereby effectively causing a shift to the right 70 of the traverse as the package builds and pro-

ducing the shape of package as shown in Figure 20.

Figure 21 shows a conical package 80 having tapered ends 81, 82 wound on a conical core 83 and this may be wound in accordance with the present invention by using a thread guiding slot 85 in plate 7 which is straight and initially axially parallel to the spindle 2 as shown in dotted lines, and this may be the same slot as slot 74 (Figure 20) which is inclined to the full line position at the completion of the winding of the package 80. However, the thread guide 5 is provided with an inclined slot 86 which crosses the slot 85 at a considerable angle at all times. As the package increases in diameter, the slot 85 is continuously and gradually inclined, causing a gradual and continuous shortening of the traverse of the thread due to the centerwise shifting of the extreme limits of the crossing T. Thus T2 shows the final left extreme crossing of the slots 85 and 86 when the slot 85 has been inclined to its extreme position, and T3 shows the extreme right hand position of the intersection for the same inclination of slot 85.

Figure 22 shows a package 90 of generally conical exterior having a tapered base 91 and a slightly concave nose 92 wound on a conical core 93, while Figure 22a shows the formation and shape of the slots for winding such a package according to the present invention. As embodied, the slot 95 is a straight slot in plate 7, aligned with the spindle axis 2 at the beginning of the winding operation, and gradually and continuously inclined, as with Figures 20 and 21. Slot 96 is formed in the reciprocable thread guide 5 and is moved back and forth across the surface of the package, with plate 7 and its slot 95 between it and the package, the thread passing through the crossing T of the slots 95 and 96. The dotted line position of slot 95 is its position at the start of the winding, while the full line position of the slot 95 is its position at the end of the winding. Slot 96 of guide 5 comprises an upper vertical portion for winding the nose 92 of the package, and a downwardly and forwardly inclined lower portion for winding the base 91 of the package. At the left of Figure 22a is shown in dotted lines the position of the slot 96 at the extreme left position of its traverse and when the slot 95 has reached its maximum inclination the crossing will lie at T2. At the right, is shown the crossing T3 with the slot 95 fully inclined and the slot 96 at its extreme right. As will be seen, the angularity of the slot 96 in cooperation with the inclination of the straight slot 95 has caused the left hand portion of the thread traverse to remain unchanged, while the right hand portion of the traverse has been considerably shortened to form the tapered base.

Figure 23 shows a package 100 which is wound on a conical core 101 and has a tapered nose 102 and a slightly convex base 103 which is perpendicular to the core 101. This package may be wound using the guide slots 104 in guide plate 7 and 105 in guide 5. Guide 7 having the slot 104 is aligned with the core axis at the beginning of the winding operation and is gradually inclined to the full line position at the end of the winding operation on the package. The lower half of the slot 105 is substantially vertical, causing no variation in the right half of the traverse of the thread at the crossing T, while the upward and rightward inclination of the upper half of the slot 105 causes a foreshortening of the left hand half of the traverse of the thread at cross-

ing T as the inclination of the slot 104 in guide 7 is increased from the dotted to the full line position with the increase in the size of the package 100.

Figure 24 of the drawings shows a dyeing package 110 which is wound on a foraminous tubular core 111 and is compressible, having the coils of thread or yarn more closely spaced near the center of the package than near the ends of the package so that the package when stacked endwise, one upon the other, and squeezed or pressed together, in the dyeing tank, produce an even density throughout each individual package and the entire length of the stacked packages, thereby facilitating the even or uniform entry of the dye solution into the packages during the dyeing operation. In forming such a package, the traverse of the guide 5 is parallel to the axis of the spindle 2 and to the surface of the core 111 and the guide 5 is reciprocated along the line H of Figure 24a. The guide plate 7 is held stationary during the winding operation by locking it against pivotal movement and by disconnecting the pulley 20 from effective connection with the plate 7. Plate 7 is provided with a slot 114 of a gradual sinusoidal shape which begins at, intersects and ends on the line H, while the guide 5 is provided with a slanting slot 115. As the slot 115 moves at a constant speed first in one direction and then in the other the point of crossing T which corresponds to the position of the thread being guided to the package is gradually shifted so as to vary its speed slightly relatively to the speed of the guide 5. At point T the thread lies at the crossing of slots 114 and 115 and its speed of traverse corresponds to the speed of the guide 5, but as the guide moves to the left and then to the right, the thread assumes the successive positions T2, T3, T4, T3, T2, T, T5, T6, T7, T6, T5, T, etc. At T2, the thread traverse is at a slightly slower speed than the guide movement, at T3 the same speed, and T4 the speed is considerably faster than that of the guide. On the reverse movement, the speed between T4 and T3 is faster, at T3 is the same, at T2 is slower, and at T is again the same as that of the guide 5 and continuing on the other side the speed decreases until T6 is reached when the speed becomes the same and increases until T7 is reached, etc., thereby spacing the coils of the wound package closer together near the center of the package and further apart near the ends of the package. Of course, the spacing may be varied by varying the shape of the slot 114 and the inclination of the slot 115.

Figure 25 shows a conical package 120 wound on a conical core 121 and having the coils of thread closer together near the base of the package and relatively widely spaced near the nose of the package. Such a package is wound with an inclined thread guide slot 124 in the thread guide 5 which is reciprocated back and forth along the package and crosses a curved slot 125 in the guide plate 7 causing the thread to be gradually wound with an increasing pitch as the thread guide 5 moves to the left and with a gradually decreasing pitch as the guide 5 moves to the right.

The invention in its broader aspects is not limited to the specific mechanisms shown and described but departures may be made therefrom within the scope of the accompanying claims without departing from the principles of the invention and without sacrificing its chief advantages.

What I claim is:

1. In a thread winding apparatus, thread traversing means including a pair of relatively movable closely adjacent substantially parallel members having crossing slots through which the thread passes, said slots being so closely adjacent that at the point of crossing they define and act as a single thread guiding opening. 5
2. In a thread winding apparatus, thread traversing means including a plurality of relatively movable members having elongated thread guiding surfaces held closely adjacent each other and inclined relatively to each other, the thread being movable along said surfaces and substantially normal thereto, said surfaces being so closely adjacent that at the point of crossing they define and act as a single thread guiding surface. 10
3. In a thread winding apparatus, thread traversing means including a plurality of relatively movable members substantially normal to the thread and having relatively angularly movable elongated thread guiding surfaces inclined relatively to each other and crossing each other at all times and means for varying the inclination of at least one of the surfaces. 15
4. In a thread winding apparatus, thread traversing means including a plurality of relatively movable members substantially normal to the thread and having thread guiding slots inclined relatively to each other and crossing each other at all times and means for varying the inclination of at least one of the slots. 20
5. In a thread winding apparatus, thread guiding means including a plurality of slotted members relatively movable to each other, means for moving one of the members back and forth along the package being wound and means for varying the inclination of one of the slots as the diameter of the package increases. 25
6. In a thread winding apparatus, thread guiding means including a plurality of slotted members relatively movable to each other and having their slots crossing, means for moving one of the members back and forth along the package being wound and means for varying the inclination of one of the slots as the diameter of the package increases. 30
7. In a thread winding apparatus, thread guiding means including a slotted plate adjacent a package being wound, a slotted plate movable back and forth along the package and means for varying the inclination of the slots in the plates. 35
8. In a thread winding apparatus, thread guiding means including a slotted plate adjacent a package being wound, a slotted plate movable back and forth along the package, the slots in the plates being inclined relative to each other to cause a displacement of the thread as it passes through both slots and is moved back and forth along the package. 40
9. In a thread winding apparatus, thread guiding means including a slotted plate adjacent a package being wound, a slotted plate movable back and forth along the package, the slots being inclined relative to each other and means for varying the relative inclination of the slots as the package increases. 45
10. In a thread winding apparatus, thread guiding means including a slotted plate adjacent a package being wound, a slotted plate movable along the package, the slots being relatively inclined and means for continuously varying the inclination on one of the slots. 50
11. In a thread winding apparatus, thread guiding means including a slotted plate adjacent a package being wound, a slotted plate movable along the package, said plates being mounted for movement relative to the package axis as the package increases and means for varying the inclination of at least one of the plates as the plates are moved relative to the package axis. 55
12. In a thread winding apparatus, thread guiding means including an elongated thread guiding surface adjacent a package being wound, an elongated thread guiding surface movable along the package, said surfaces being inclined relative to each other and means for varying the relative inclination of the surfaces as the package increases. 60
13. Winding apparatus including in combination means for rotatably supporting a core on which a package is wound, and thread guiding means mounted to move toward and away from the core, said guiding means including a slotted member movable back and forth along the package and a slotted plate adjacent to the package having its slot inclined to the first slot and means controlled by the movement of the guiding means toward and away from the core for varying the traverse of the thread by said guiding means. 65
14. Winding apparatus including in combination means for rotatably supporting a core on which a package is wound, and thread guiding means mounted to move toward and away from the core, said guiding means including a slotted member movable back and forth along the package and a thread guiding surface adjacent to the package having its guiding surface inclined to the slot and means for varying the relative inclination of said slotted member and thread guiding surface as the guiding means are moved with respect to the core. 70
15. Winding apparatus including in combination means for rotatably supporting a core on which a package is wound, and thread guiding means mounted to move toward and away from the core, said guiding means including a slotted member movable back and forth along the package, a thread guiding surface pivotally mounted to remain in contact with the surface of the package as the shape of the package changes, and adjacent to the package having a guiding surface relatively inclined to the slot, and means for varying the relative inclination as the guiding means move relatively to the core. 75
16. Winding apparatus including in combination means for rotatably supporting a core on which a package is wound, and thread guiding means mounted to move toward and away from the core, said guiding means including a slotted member movable back and forth along the package, a thread guiding slotted member pivotally mounted so as to remain in contact with the surface of the package as the shape of the package changes, and adjacent to the package, and means for varying the inclination of the slot in the second member to vary the traverse of the thread along the package. 80
17. In a thread winding apparatus, in combination, means for rotatably supporting a core on which a package is to be wound, a thread guide movable back and forth along the package and having an elongated slot inclined relatively to the path of guide movement and means between the thread guide and package for varying the position of the thread in the guide slot 85

as the thread is moved by the guide along the package.

18. In a thread winding apparatus, in combination, means for rotatably supporting a core on which a package is to be wound, a thread guide movable back and forth along the package and having an elongated slot inclined relatively to the path of guide movement and means adjacent to the thread guide and package for changing the position of the thread in the guide slot as the thread is moved by the guide along the package.

19. In a thread winding apparatus, in combination,

means for rotatably supporting a core on which a package is to be wound about a substantially horizontal axis, a thread guide movable back and forth along the package, a plate 5 between the thread guide and the package and yieldably held against the package, and means for pivoting the plate about a substantially vertical axis parallel to a plane tangent to the surface of the package whereby the pressure of the plate along the surface of the package may be 10 equalized as the shape of the package changes during winding.

LESTER CAMPBELL.
